METAL CONTAINER

William W. Hodgson, Chicago, Ill., assignor to
 Continental Can Company, Inc., New York,
 N. Y., a corporation of New York

Application January 9, 1933, Serial No. 656,926

1 Claim. (CL 220—54)

The invention relates to new and useful improvements in metal containers, and more particularly to a container having a tearing strip which may be removed in the opening of the 5 container.

An object of the invention is to provide a metal container of the above type with an inserted collar made from a strip of metal having the ends thereof abutted and interengaged so as to prevent lateral movement of one end relative to the 10 other.

A further object of the invention is to provide a container of the above type wherein the ends of the collar are so inter-engaged as to prevent separation of the ends as well as lateral movement 15 of one relative to the other.

These and other objects will in part be obvious and will in part be hereinafter more fully disclosed.

20 In the drawing—

Figure 1 is a vertical sectional view through the container embodying the improvements;

Fig. 2 is a sectional view through a portion of a collar embodying the improvements;

Fig. 3 is a view showing the two ends of the strip forming the collar, said ends being separated;

Fig. 4 is a view showing the ends of the strip interengaged and joined by soldering;

Fig. 5 is an edge view of the parts shown in Fig. 4;

Fig. 6 is a view showing a slightly modified form of inter-engaging connection joining the ends of the strip from which the collar is made, 35 and

Fig. 7 is a view similar to Fig. 6, showing a further modified form of inter-engaging connection.

The invention is embodied in a metal container 40 which includes a body portion 1 having an end 2 secured thereto by a double seam 3. There is, of course, a bottom end similarly secured to the body of the container. The body wall is scored at 4 adjacent the double seam, and at 5, setting off therebetween a rip strip to which a key may be applied for tearing the same away to open the container. This is the usual form of easy opening rip strip container, and further description thereof is not thought necessary. Located 45 within the body of the container is a collar 6 which is preferably made of a diameter slightly greater than the inner diameter of the container body so that when the collar is forced into the container it will frictionally grip the wall of the container and be held in place therein. It is

understood, however, that the collar may be held in other ways than by a frictional grip. The body wall of the container is preferably provided with a bead 7 which forms a shoulder, and the collar is preferably forced into the container until it contacts with said shoulder. When the collar is placed in the container, it extends to a point adjacent the upper score line 4. The upper part 8 of the collar, as shown, is inset so as to provide a space therebetween and the wall of the container. This inset portion is located above the lower score line 5. The collar at the upper end thereof is rolled into a hollow strengthening bead 9. The container end 2 is shaped by drawing so as to provide a depending portion 10 which extends into the container body in rear of the tearing strip. This depending portion also lies between the inset portion of the collar and the body wall.

The present invention is directed particularly to the manner in which the ends of the collar are joined, and it will be understood that the particular shaping of the collar and the can end for reclosure purposes may be greatly varied without departing from the spirit of the invention as set forth in the appended claim. The collar is made from a strip of metal. The ends of the strip are joined, after which the collar is shaped. The strip of metal from which the collar 6 is formed is indicated at 10 in the drawing. In the preferred 30 form of the invention, one end of the strip is provided with a dove-tailed shaped projection 10^a, while the other end of the strip is provided with a similarly shaped recess 10^b. When the projection is inserted in the recess, the ends are 35 joined. The ends are in the same plane and they abut, making contact all the way across the strip. This particular shaping of the inter-engaging parts will hold the ends so as not only to 40 prevent separation, when strains are applied to the collar which tend to expand the same, but also to prevent lateral movement of one end relative to the other. It holds the two ends firmly abutted and in alignment. It is understood, of course, that when the two ends are joined, the 45 collar blank is cylindrical in form. In order to prevent the ends from slipping out of alignment radially, solder may be applied as indicated at 11 in Figures 4 and 5. This will firmly bond together the inter-engaged parts and prevent them 50 from slipping out of engagement. Instead of soldering, it is understood, of course, the metal parts might be joined by welding, or in any other way wherein fused metal bonds together the parts. After the ends of the strip have been joined, then 55

the cylindrically formed blank is subjected to die pressure for insetting the upper portion 4^a thereof, as shown in Fig. 2, and for rolling the hollow bead 8 at the upper end portion thereof 5 for strengthening the same. This completes the collar ready for insertion in the container body.

In Fig. 6 of the drawing, there are shown two projecting portions 12, 12 on one end of the collar strip 10, and two corresponding recesses 13, 10 13 on the other end of said strip. These projecting portions are shaped so as to provide relatively large rounded heads with a narrow neck so that when the projections are nested in the recesses, the ends of the strip will be held from 15 separation in a direction lengthwise of the strip, as well as from movement laterally in the plane of the strip. As shown in Fig. 6, solder is applied as indicated at 14 for joining the ends. The ends, however, may be secured in their nested 20 or inter-engaged position in any suitable way, either by solder bonding, welding, or by a frictional oversize fit between the parts. The same is true of the construction shown in Fig. 3.

In Fig. 7 there is shown a slightly further modified form of the inter-engaging parts. The projecting members 15, 15 carried by one end of the strip 10 are spaced, but are of substantially the same width in the plane of the strip throughout. The recesses are similarly shaped so that 30 there is an abutted connection between the two ends of the strip. These projections will prevent any possible movement of the ends of the strip in the plane of the strip out of alignment. The solder bond may be used for joining the 35 ends of the strip as indicated at 16. Instead of the solder bond, the ends may be welded, and it is the fused metal bonding the ends together that prevents the ends from separating. It will be understood that the shaping of the projecting portions and the recesses may be greatly varied 40 from that disclosed in the drawing. The essential features reside in the providing of one or more projections on one end with similarly shaped

recesses on the other end, so that when they are nested together or inter-engaged, there will be an abutted connection between the ends of the strip. When the strip is forced into the container, it is necessarily put under strain, which tends to contract the collar. This strain on the collar is taken in the present construction through the abutted end-on contact all the way across the strip. There is also a strain laterally of the collar in the plane of the strip during the handling and the insertion of the collar and the inter-engaged parts will hold the ends in perfect alignment.

It is obvious that minor changes in the shaping of the parts and the details of construction 15 may be made without departing from the spirit of the invention as set forth in the appended claim.

Having thus described the invention, what I claim as new and desire to secure by Letters 20 Patent, is—

A metal container comprising a body portion, an end secured thereto by seaming said body portion having score lines adjacent one end thereof of forming a rip strip, a collar disposed within 25 said body so that the upper end extends above the lower score line, said collar being formed from a strip having the ends thereof abutted so that said collar is of uniform diameter throughout the entire extent of the collar, said collar being dimensioned so as to frictionally contact with the inner wall of the container whereby said collar is held within the container, one of said abutted ends of the collar having a projecting portion adapted to fit within a recess formed in 30 the other end of the collar strip, said projecting portion and recess being shaped so as to prevent separation of the ends or lateral movement of one end relative to the other in an endwise direction and a fused metal bond for securing said 35 interengaging portions together.

WILLIAM W. HODGSON.
